UNITED STATES PATENT OFFICE

HARVEY L. BOYER, OF KUNKLETON, PENNSYLVANIA

REGISTERING AND PRINTING DEVICE

Application filed December 31, 1926. Serial No. 158,347.

My invention relates to adding or totalizing devices, wherein number-setting wheels or disks are employed to move printing wheels or disks into printing position and at the same time move the wheels or disks of a totalizing train into registering position, and wherein retractive movement of the number-setting wheels or disks to zero position will only affect the movement of the printing wheels or disks which will also be moved to zero position; the mechanism including means for holding the wheels or disks of the totalizing train against retraction, so that various sums or amounts individually set up on the number-setting wheels or disks may be individually reproduced by the printing wheels or disks and successively added into the totalizing train.

One object of my invention is to provide a portable, registering and printing device of a size that may be carried in the pocket of the user; such device having been especially designed for employment by collectors, salesmen, and the like, for adding their receipts as the same are collected. It may also be employed to add or totalize amounts representing units of any character.

A further object of my invention is to provide a device of this character with means whereby separate amounts representing the individual sums collected, or other units, may be printed in receipt books or on receipt cards, or the like, and wherein such individual sums or other units are added into a totalizing train of registering wheels or disks.

These and other features of my invention are more fully described hereinafter; reference being had to the accompanying drawings, in which:

Figure 1, is a front elevation of the mechanism of a registering and printing device within the scope of my invention, with the casing shown in section,

Fig. 2, is a sectional elevation taken on the line II-II, Fig. 1,

Fig. 3, is a similar sectional elevation, taken on the line III-III, Fig. 1,

Fig. 4, is a plan view of the mechanism of my improved registering device developed in a single plane,

Fig. 5, is a sectional elevation, taken on the line V-V, looking in the direction of the arrows, Fig. 4.

Fig. 6, is a sectional view on the line VI-VI, Fig. 5, and

Fig. 7, is a view looking down upon the complete structure, showing the openings through which the wheels or disks of the setting train and the totalizing train may be viewed, and the base line for the setting train.

In the development of my improved structure, the object has been to provide simple and effective means whereby collectors and other persons giving receipts for sums collected, or other persons desiring to totalize units of any character, may have a totalizing device of convenient size to be carried in the pocket, with which will be combined printing means so that individual sums representing amounts collected from various customers, subscribers and/or the like, or units of any character, may be printed upon receipt cards, in receipt books, and the like, and such amounts added into a totalizing train of registering wheels. While the structure I have illustrated is capable of totalizing units or amounts up to 99999, or sums representing money up to \$999.99, it will be understood that mechanism including a registering train capable of indicating higher amounts, is within the scope of my invention; the parts necessary to indicate, print and register higher amounts being duplicates of the parts disclosed.

In the device forming the subject of my invention, there are a series of number-setting wheels or disks; a series of number printing wheels or disks; and a series of number totalizing wheels or disks, with which are associated gears or toothed wheels, with cooperating pinions between said gears or toothed wheels whereby any movement of the number-setting wheels or disks will be transmitted to the printing wheels or disks, thereby placing the same in position to print individually the various amounts or sums indicated by the setting wheels, and at the same time the wheels or disks of the totalizing train will be advanced for the purpose of adding thereto each individual amount or

sum determined by the position of the number-setting wheels or disks and the printing wheels or disks.

My improved device comprises a suitable casing or shell, which may consist of end walls A, A, and a suitably shaped cover B, extending between these end walls; said cover being apertured at the points a and b, and provided with hinged covering means for the type faces of the printing wheels, which may be in the form of a pair of covers C, hinged at c, and having a suitable retaining catch.

The number-setting wheels or disks are indicated generally at 1; the printing wheels or disks are indicated generally at 2, and the totalizing wheels or disks are indicated generally at 3; each of said reference numerals being provided with suitable exponents whereby the several wheels or disks may be differentiated from each other.

Secured in the end walls A, A, of the casing are a series of cross rods, indicated at 4, 5, 6, 7, 8 and 9. The rod 4 carries the number-setting wheels or disks, 1, 1^a, 1^b, et seq., each numbered from "1" to "0", constituting the number-setting wheels or disks; each of said number-setting wheels or disks being operatively connected to a pinion or gear 4^a, and being independently movable with said pinions or gears on said rod 4, or on a sleeve mounted thereon. Each of these elements has a notched flange 4^b of the type common to dating stamps whereby they may be manually operated, or these wheels or disks 1, 1^a, 1^b, et seq., may be provided with recesses 4^c, in which a pencil point or similar instrument may be introduced to turn the same step-by-step. To prevent movement of the number-setting wheels beyond zero position, the flanges 4^b may be provided with stops 4^d, to engage the wall of the casing; the wheels or disks in such position having their zero indication adjacent to a base line indicated in Fig. 7. By preference light spring pawls 4^e, mounted on a cross rod 10, also secured to the end walls A, A, may be employed to hold these number-setting wheels or disks 1, 1^a, et seq., in their adjusted positions, and the face of said number-setting wheels or disks 1, 1^a, 1^b, et seq., may be provided with suitable grooves 4^f, in line with the recesses 4^c, in which such pawls may seat; such engagement being sufficient to prevent accidental movement in either direction, but not preventing the manual operation of said number-setting wheels or disks.

The rod 5 carries a series of printing wheels or disks 2, 2^a, 2^b, et seq., each provided with printing types, indicated at d, reading from "1" to "0" inclusive, and each of these printing wheels or disks 2, 2^a, 2^b, et seq., is operatively connected to a pinion or gear 5^a; said printing wheels or disks and their connected pinions or gears being loose upon the rod 5.

In addition, each of these printing wheels

or disks, or the pinions connected thereto, carries a ratchet wheel 5^b, which is engaged by a spring pawl 5^c, carried by a gear or pinion 12, independently movable on said rod 5, (or a sleeve carried by the same), so that movement imparted to any one of the printing wheels or disks 2, 2^a, 2^b, et seq., in one direction will move one of said pinions 12, through the engagement of the pawl carried thereby with the ratchet wheel 5^b, connected to the printing wheel or disk moved, but when reverse movement is imparted to said printing wheels or disks to restore them to zero position, when the number-setting wheels or disks are moved to zero position adjacent said base line no movement will be imparted to said gears or pinions 12; the ratchet wheels 5^b, carried by the gears or pinions 5^a, slipping past the spring pawls 5^c carried by said pinions 12, without affecting their position on the shaft.

The rod 6 is disposed between the rods 4 and 5, and carries pinions 6^a, loose thereon and meshing with the pinions 4^a and 5^a, of the wheels or disks 1, 1^a, 1^b, et seq., and the wheels or disks 2, 2^a, 2^b, et seq., respectively, so that any movement imparted to said number-setting wheels or disks will be transmitted to the printing wheels or disks; the latter being arranged to turn in either direction but only imparting movement to the pinions 12, which in turn effect movement of the wheels or disks 3, 3^a, 3^b, et seq., of the totalizing train through the pawl and ratchet mechanism noted, when moving in one direction.

The rod 7 carries the totalizing train, consisting of the registering wheels or disks 3, 3^a, 3^b, et seq., and each of these wheels is operatively connected to a pinion 7^a, meshing with an intermediate pinion 8^a, mounted on the cross rod 8, (disposed between the rods 7 and 9), whereby motion imparted by the number-setting wheels or disks to the printing wheels or disks may be transmitted to the wheels or disks of the totalizing train; said pinions 8^a, meshing with the gears or pinions 12, mounted on the rod 5, and transmitting to the wheels or disks of the totalizing train, the movement imparted to the latter pinions or gears, 12. Each unit of the totalizing train, with the exception of the last, consists of a registering wheel or disk 3, 3^a, 3^b, et seq., a pinion 7^a, and a wheel or disk 13, having a single tooth 13^a.

The cross rod 9, mounted in the upper part of the casing, carries a series of cooperating devices whereby movement may be transmitted from the pinions 7^a, associated with each wheel or disk of the totalizing train, to the next adjacent wheel or disk thereof. Mounted on said rod 9 are a series of elements; each comprising a collar 9^a, carrying at one end a pinion 9^b, and at the opposite end a ratchet or star-toothed wheel 9^c. Mount-

ed also on said rod 9 alongside the ratchet wheels 9^c, are other ratchet wheels 9^d, each carrying a pawl 9^e, in engagement with the teeth of the ratchet wheels 9^c. The teeth of the ratchet wheels 9^d are in aligned position for engagement by the single-toothed wheels 13, associated with said totalizing wheels 3, 3^a, 3^b, et seq. When a complete revolution is imparted to the unit registering wheel 3, for instance, the single tooth 13^a of the wheel or disk 13 associated with said registering wheel 3 will, upon the next movement imparted to said registering wheel 3, move the star wheel 9^a one tooth; imparting similar movement to 15 the ratchet wheel 9^c through the pawl 9^e, and the pinion 9^b, meshing with the pinion 7^a, associated with the second registering wheel or disk 3^a, will impart one-tenth of a revolution thereto.

20 If any motion is imparted to these elements in another relation as, for instance, by one of the pinions 7^a, imparting movement to a pinion 9^b, in adding from left to right, the ratchet wheel 9^c will turn without affecting 25 the position of the wheel or disk of the totalizing train to the right of the one associated with said pinion 7^a, which is being actuated. No motion will be imparted by any wheel of the totalizing train, when adding from right 30 to left, until the wheel 13 associated therewith is in such position that its tooth 13^a, will engage and turn the ratchet wheel 9^d, which will impart its movement to the ratchet wheel 9^c, and thence to the pinion 9^b, through 35 the pawl 9^e, carried by said ratchet wheel 9^d; said pinion 9^b meshing with a pinion 7^a and moving the same with the totalizing wheel or disk associated therewith.

When the setting or indicating disk or 40 wheel 1 is turned in the direction indicated by the arrow, Fig. 2, the pinion or gear 4^a, operatively connected thereto will rotate in the same direction, and such gear or pinion, meshing with the pinion 6^a, and the latter 45 meshing with the pinion 5^a, associated with the printing wheel or disk 2, will bring one of the numbers of said printing wheel or disk indicated at *d*, into printing position. The ten-toothed ratchet wheel 5^b, attached to the 50 pinion 12, will be moved by the pinion 5^a, through the medium of the pawl 5^c, and said pinion 12, meshing with the pinion 8^a, which in turn meshes with the pinion 7^a connected to the registering or totalizing disk 3, will 55 impart movement to the latter.

Therefore should the number "9" of the "cents" or "unit" setting wheel or disk 1, be brought to the position adjacent the base line, then the number "9" of the printing wheel or disk will appear in the printing position, and the number "9" will also appear at the registering position of the totalizing train.

The registering wheels are prevented from accidental movement by means of pawls 14, 60 which may be carried by a cross rod 15, and

since the pinions 4^a, 6^a, and 5^a, are in direct contact with each other, the number setting or indicating wheel 1 when brought back to the zero position, will carry with it the printing wheel 2. This movement of setting back 70 to zero does not affect the position of the number registered indicated on the registering wheel, because the ratchet wheel 5^b, may move backward with relation to the pawl 5^c, carried by the pinion 12, without imparting 75 movement to the latter.

Should the number 9 of the "cent" or "unit" setting wheel or disk 1 be again brought into the indicating position, then the same rotation described above will be carried out, together with another element entering into play, to wit: the one-toothed wheel 13, which, with the pinion 7^a, is fastened to the totalizing or registering wheel 3, will engage one of the teeth of the ratchet wheel 9^d, which will 80 rotate the ratchet wheel 9^c, and with it the pinion 9^b. The pinion 9^b, meshes with the pinion 7^a associated with the second column or train of pinions including the totalizing wheels or disk 3^a, and moves the latter one 85 unit space, and therefore the second setting of the unit wheel or disk 1, to the number "9" will produce on the first two wheels or disks of the registering train the sum "18".

In Fig. 1, the number-setting wheels or 90 disks are indicated as having been set with respect to the base line to indicate "545.20"; the printing wheels or disks are simultaneously moved to bring the same numbers into printing position and, of course, the same 95 numbers will appear on the wheels or disks of the totalizing train and will remain there while the number-setting wheels or disks, with the printing wheels or disks, are moved 100 back to zero position.

Now if it be desired to add to this sum or amount, the figure "256.60", for instance, the 105 following operation will take place:

This addition will be from right to left, with the numbers of the setting wheels or 110 disks set at zero with respect to the base line, no movement of the first or unit wheel or disk 1 will be required. Upon moving the second setting wheel or disk, 1^a, to a position to indicate "6" at the base line, such action will 115 move the printing wheel or disk 1^a from its zero position to a position whereby it may print "6", and at the same time the wheel or disk 3^a of the totalizing train will be moved six spaces ahead which will change 120 the "2" of the "tens" position to "8", making the amount indicated 545.80. When "6" of the third setting wheel or disk 1^b is brought to indicating position with respect to the base line, the printing wheel or disk 2^b is brought to the "6" position and the registering wheel or disk 3^b will be moved six spaces 125 which action will change the "5" of the third registering wheel or disk 3^b to "1", and the "4" of the fourth registering wheel or disk 3^c, 130

to "5", making the amount "551.80". When the "5" of the fourth place is added by bringing the fourth setting wheel 1^c into position, to indicate "5" adjacent the base line, a similar number of the printing wheel or disc 2^c , will appear in printing position, while the fourth wheel or disk 3^c of the registering train will have a five space movement and the "0" will be brought to registering position in the fourth place, while the fifth registering wheel or disk 3^a , will be moved one space; making the amount indicated 601.80. Finally, when the setting wheel 1^a is moved to position the "2" of the fifth place with respect to the base line, the printing wheel or disk 2^a will be similarly moved, while the fifth registering wheel or disk 3^a will be moved two spaces to indicate "8", and the amount indicated on the registering train will be "801.80", while the printing wheels or disks will be in position to print "256.60"; which has been added to the previous amount indicated by the registering train, i. e., "545.20".

25 In adding from right to left the process is quite simple, as motion is first imparted to the "hundredths" wheel or disk of the setting train and thence to the unit wheel or disk of the totalizing train and the same will be moved step by step, depending upon the amount proposed to be added to the totalizing train, as indicated by the setting wheel. Upon completing a single revolution, such "hundredths" wheel of the totalizing train imparts motion to the "tenths" wheel, which movement is effected by the single toothed pinion associated with the "hundredths" wheel, engaging a tooth of the ratchet wheel 9^a and the latter transmitting movement to the pinion 9^b meshing with the pinion or gear 7^a carried by the "tenths" wheel; hence one-tenth of a revolution imparted to the ratchet element operated by the "hundredths" wheel will, by the cooperation of the pinions mentioned, impart one-tenth of a revolution to the "tenths" wheel, and such operation will be duplicated in the successive operations of the "units", "tens" and "hundreds" wheels of the totalizing train.

50 Under some conditions and in the hands of an unskilled operator it may happen that there will be a tendency to add the sums from left to right, or to add the numerals representing parts of the sums indifferently. Under these circumstances, assuming for instance that the totalizing train reads 43.87 and it is desired to add to that the sum 18.65. Now, if the first numeral to the left, in other words the "1", of the number-setting wheel or disk 1^c is brought to the base position, this will effect movement of the "tens" (or fourth) wheel or disk 3^c , of the totalizing set through the normal gear train, in other words, a direct connection, and the numeral "5" will show on said wheel or disk 3^c of the

totalizing set. When the setting wheel or disk 1^b of the "units" (or third) place is operated to bring the numeral "8" in line with the numeral "1" of the setting wheel or disk 1^c , such positioning of the setting wheel or disk 1^b will have effected movement of the totalizing wheel or disk 3^b , eight-tenths of a revolution which, plus the three-tenths already turned with relation to its single toothed wheel, will bring about an addition whereby the "tens" and the "units" wheels or disks (the fourth and third places) of the totalizing set, will read "61". This means, therefore, that the "units" wheel after completing its revolution must impart one-tenth of a revolution to the "tens" (or fourth) wheel or disk but in order that such movement of the "units" (or third) wheel or disk shall not affect in any way motion of the "tenths" (or second) wheel or disk the ratchet wheel 9^a which has been moved by the single toothed pinion of the "units" wheel is so connected to the ratchet wheel 9^c , that the single tooth 13^a of the wheel 13 will not be moved and if it happens to lie adjacent to the ratchet wheel 9^a the movement of the latter will be halted; the pawl carried thereby slipping on the teeth of the ratchet 9^c , thereby preventing the operation of the "tenths" wheel and simply adding into the "units" wheel.

In order that the type faces of the printing wheels may be inked properly for printing purposes, the casing may be provided with inking rolls 20, disposed on each side of the printing wheels; said rolls being carried by cross bars 21 and being free to rotate by contact with the type faces of the printing wheels. As the lower type faces, normally out of contact with the inking rolls may not receive ink therefrom, I preferably provide the inner surface of the cover sections C with inking pads 21 a , as clearly indicated in Figs. 2 and 3.

I claim:

1. In a pocket printing device, the combination of a supporting casing having end walls, a cross rod secured to said end walls, a series of number setting wheels rotatably mounted on said cross rod, gear wheels operatively connected to said number setting wheels, a second cross rod, a series of printing wheels rotatably mounted on said second cross rod, gear wheels operatively connected to said printing wheels, a series of intermediate pinions meshing with the respective gear wheels of the setting wheels and the printing wheels whereby movement imparted to said setting wheels may be transmitted to the printing wheels, inking rolls set on opposite sides of the printing wheels; the casing having curved pockets for the reception of said inking rolls and an opening to expose the edges of the printing wheels, and a closure

for said opening comprising a pair of sections hinged to the wall of the casing.

2. In an amount setting and printing device adapted to be carried in the pocket, the combination of a supporting casing having end walls, a cross rod secured in said end walls, a series of number setting wheels mounted on said cross rod, gear wheels operatively connected to each of said setting wheels, a second cross rod secured in said end walls, a series of printing wheels mounted on said second rod, gear wheels operatively connected to each of said printing wheels, an intermediate rod disposed between the other rods, a series of pinions mounted on said intermediate rod and meshing with the respective gears of the number setting wheels and the gears of the printing wheels whereby movement of the number setting wheels may be transmitted to the printing wheels, inking rolls set at opposite sides of the printing wheels; the casing having an opening to expose the edges of said printing wheels, a displaceable cover comprising a pair of sections hinged to the wall of the casing for said opening, and inking pads carried by the inner side of the hinged sections comprising said cover.

3. In a pocket printing device, the combination of a supporting casing having end walls, a cross rod secured to said end walls, a series of number setting wheels rotatably mounted on said cross rod, said number setting wheels having notched edges with radial recesses extending from the roots of said notches, pawls arranged to engage said notched edges, gear wheels operatively connected to said number setting wheels, a second cross rod, a series of printing wheels rotatably mounted on said second cross rod, gear wheels operatively connected to said printing wheels, a series of intermediate pinions meshing with the respective gear wheels of the setting wheels and the printing wheels whereby movement imparted to said setting wheels may be transmitted to the printing wheels, inking rolls set on opposite sides of the printing wheels; the casing having an opening to expose the edges of the printing wheels, and a closure for said opening comprising a pair of sections hinged to the wall of the casing.

In witness whereof I have signed this specification.

HARVEY L. BOYER.
